UNITED STATES PATENT OFFICE.

FRANK SAXON, OF WORTHINGTON, MINNESOTA.

COG-WHEEL.

SPECIFICATION forming part of Letters Patent No. 487,129, dated November 29, 1892.

Application filed March 22, 1892. Serial No. 425,940. (No model.)

To all whom it may concern:

Be it known that I, FRANK SAXON, of 5
Worthington, in the county of Nobles and
State of Minnesota, have invented a new and
useful Improvement in Cog-Wheels, of which
the following is a full, clear, and exact de-
scription.

My invention relates to an improvement in
10 cog-wheels, and has for its object to construct
either a plain or a compensating cog-wheel in
two sections having cushions intervening be-
tween them, so that when the wheel is employed
to communicate motion suddenly to any portion
15 of the machinery it will not impart to the
said parts any sudden or injurious shock; and
a further object of the invention is to provide
a compensating cog-wheel having the pecu-
liarities above described and especially adapt-
20 ed for use in connection with agricultural en-
gines or road-engines.

The invention consists in the novel construc-
tion and combination of the several parts, as
will be hereinafter fully set forth, and pointed
out in the claims.

Reference is to be had to the accompanying
25 drawings, forming a part of this specification,
in which similar figures and letters of refer-
ence indicate corresponding parts in all the
views.

Figure 1 is a side elevation of a cog-wheel
30 constructed in accordance with my invention,
the cover-plate for the spring-receiving cham-
bers being removed. Fig. 2 is a horizontal
35 section through a compensating cog-wheel
embodying the features of the invention, and
Fig. 3 is a segment of the cover-plate for the
spring-chambers.

The cog-wheel is constructed, primarily, in
40 two sections, an inner section A and an outer
section B, one section being peripherally fit-
ted to the other. Upon the periphery of the
inner section, which is adapted to be secured
45 to the shaft or to run loosely thereon, a series
of spurs or lugs 10 is formed at predetermined
intervals apart, and when the cog is to be used
as a compensating one this inner section is
50 provided with a series of openings 11, adapted
to receive pinions 12, as shown in Fig. 2.
When the pinions are to be employed in con-
nection with the cog-wheel, in the base-wall
55 of each opening 11 a socket 12^a is produced,
adapted to receive the inner trunnion 13 of

the cog-wheel, and a second socket 14 is pro-
duced in one face of the inner section at its
periphery adjacent to and in the outer walls 55
of the openings 11. Around this socket a
countersink 15^a is made, and in the sockets
14 the outer trunnions 15 of the pinions are
located. The countersinks 15^a are adapted
to receive blocks 16, which confine the outer 60
trunnions of the pinions in their sockets. The
pinions shown in Fig. 2 are beveled pinions,
as these are the kind ordinarily employed.

The section B of the wheel upon its periph-
ery is provided with cogs 17, while in one side 65
at the inner wall a series of chambers 18 is
produced, the said chambers being divided
by lug-like partitions 19. When the two sec-
tions are placed in positive contact—that is
70 to say, when the inner wall of the outer sec-
tion is brought into engagement with the per-
iphery of the inner section of the wheel—the
lugs 10 upon the inner section will extend one
75 within each chamber 18 of the outer section,
across the central portion thereof, as shown
in Fig. 1, the lugs 10 of the inner section be-
ing so formed upon the periphery of that sec-
tion that they will readily enter the cham-
bers. Thus between each two lugs or parti-
tions 19 of the outer section a lug 10 of the 80
inner section is located, and between each
lug-like partition of the outer section and
each lug 10 of the inner section of the wheel
a spring 20 is located in the chambers 18, a
85 sufficient number of springs being employed
to fill those portions of the chambers not filled
by the lugs. Thus it will be observed that a
spring or cushion connection is made between
the sections of the wheel and that when the
90 outer section is turned it will not move the
inner section until the springs are compressed
in the direction of the required movement
and to their full extent, and even at that time
force will be exerted by the outer section
95 through the medium of the cushion and no
sudden shock or jar will be imparted to the
shaft with which the wheel is connected or
to a meshing wheel. The springs are held
in position in the chambers 18 by cover-plates
100 21, bolted or otherwise secured to the lug-like
partitions 19 of the outer section and to the
surface of said section near the outer wall
of the chambers, as shown at both sides of
Fig. 2.

When the wheel is employed as a compensating one, carrying the pinions 12, it may be loosely mounted upon a shaft 22, as shown in Fig. 2, and at one side of the wheel a beveled gear 23 may be loosely mounted upon the shaft, the said beveled gear meshing with the pinions 12 and being driven from any convenient gear or pinion, while at the opposite side of the wheel a beveled gear 24, also meshing with the pinions 12, is secured upon the shaft.

In the operation of such a wheel friction exerted upon the loosely-mounted beveled gear 23 when the cushioned cog-wheel is revolved causes the pinions 12 carried thereby to be also revolved by contact with the loosely-mounted pinion 23, and the pinions will convey motion to the gear 24, secured upon the shaft, and will revolve the latter.

Having thus described my invention, I claim as new and desire to secure by Letters Patent—

1. A compensating cog-wheel comprising an outer section provided with a plurality of chambers, an inner section provided with pinions mounted therein and with lugs projecting into the chambers of the outer section,

and springs in the chambers of the said outer sections between the partitions thereof and the lugs of the inner section, substantially as 30 described.

2. A compensating cog-wheel consisting of an inner section and an outer section, the inner wall of the outer section engaging with the peripheral surface of the inner section, 35 the outer section at its inner wall being provided with chambers separated by partitions, the inner section being provided with lugs entering the chambers of the outer section between their partitions, the inner section 40 being also provided with openings in which pinions are journaled, springs located in the chambers of the outer section, each having bearing against a partition of the chambers and the lug of the inner section contained 45 therein, and a cover-plate adapted to conceal the springs, said plate being attached to the outer section of the wheel, substantially as and for the purpose set forth.

FRANK SAXON.
